UNITED STATES PATENT OFFICE.

JOHN COLLIS, OF DES MOINES, IOWA, ASSIGNOR TO WM. P. COLLIS, OF NEW YORK, N. Y.

PACKLESS RADIATOR-VALVE.

No. 877,051.

Specification of Letters Patent.

Patented Jan. 21, 1908.

Application filed July 24, 1906. Serial No. 327,583.

To all whom it may concern:

Be it known that I, JOHN COLLIS, a citizen of the United States, residing at Des Moines, in the county of Polk and State of Iowa, have 5 invented a certain new and useful Packless Radiator-Valve, of which the following is a specification.

The object of my invention is to provide a valve for radiators in which the movement of 10 the valve on its seat as required to open and close the passage-way through the valve chamber is in a rotary direction and the pressure of the heating medium upon the valve in a direction tending to raise it from its seat is 15 counterbalanced by a pressure disk so arranged as to hold the valve to its seat with a pressure in excess of the pressure applied to the valve in a direction tending to raise it from its seat, so that when there is a light 20 pressure of the heating medium the valve will be held to its seat with a light pressure, and when there is a heavy pressure of the heating medium, the counterbalancing pressure disk will exert a strong pressure in a direction 25 holding the valve to its seat.

A further object is to provide a valve of this kind of simple, durable and inexpensive construction in which all of the parts are 30 readily accessible so that they may be replaced or repaired easily and quickly.

My invention consists in the construction, arrangement, and combination of the various parts of the valve, whereby the objects contemplated are attained, as hereinafter more 35 fully set forth, pointed out in my claims and illustrated in the accompanying drawings, in which—

Figure 1 shows a vertical, central, sectional view of a packless radiator valve embodying 40 my invention. Fig. 2 shows a top or plan view of same with the valve cover, the valve chamber and valve removed. Fig. 3 shows an inverted plan view of the valve chamber and valve. Fig. 4 shows a detail, perspective 45 view of the valve detached from the valve casing and valve chamber, and Fig. 5 shows a side elevation of a radiator with my improved valve applied thereto as in practical use.

Referring to the accompanying drawings, 50 I have used the reference numeral 10 to indicate the body portion of the valve casing. This body portion is substantially cylindrical in shape and is provided at its top with a circular screw threaded flange 11. The interior of the valve is open, and at one end is an inlet opening 12 for a heating medium to

which a nipple 13 may be screwed, which nipple may be connected with an elbow 14 to receive a supply pipe 15. Between the inlet opening 12 and the circular flange 11 is 60 a disk-shaped flat partition 16 having two segmental openings 17 and 18 therein on opposite sides of its center. The top of this partition 16 is ground smooth to receive the valve holder, hereinafter described. Surrounding the opening 18 is a partition 19 65 forming an outlet passage-way 20 communicating only with the said opening 18, and secured to the passage-way 20 is a union 21 so that the valve may be connected with a radiator in the usual way. By means of this partition 19 the interior of the valve casing is so arranged that the inlet pipe 12 communicates with the interior of the valve casing and with the opening 17 while the outlet pipe 70 75 communicates only with the opening 18, and not with the interior of the valve casing below said opening. Formed on the bottom of the valve casing is a circular flange 22 projected below the inlet opening 12 and of a 80 diameter greater than the circular flange 11. A cap 23 is screwed to said flange to close its lower end, and in this cap 23 is a pet-cock 24 for drainage purposes.

Screwed to the circular flange 11 on top of 85 the valve chamber is a valve cover or bonnet 25 having a smooth central opening to receive the valve stem 26. This stem is provided at its top with a hand wheel 27 and the stem extends through the partition 16 to a 90 point near the cap 23. Formed on or fixed to the upper portion of the valve stem 26 is 95 a hemi-spherical valve holder 28 having a broad flat base 29 ground smooth on its under surface to fit on top of the partition 16 outside of the openings 17 and 18. Fixed to the interior of the holder 28 is a downwardly 100 projecting guide 30 of angular form, and the valve proper, indicated by the numeral 31, is segmental in outline, flat on its under surface and provided with an angular socket 32 to project upwardly and to slidably receive the guide 30. Said parts are so arranged 105 that the valve 31 may be moved to cover either the opening 17 or the opening 18, or may be made to stand in position uncovering both of said openings.

Mounted on the lower end of the valve stem 26 is a flat pressure disk 33 having a packing ring 34 in its periphery designed to 110 rest against the interior of the circular flange 22 and to prevent leakage of the heating me-

dium between the periphery of the disk and the interior of said flange. This disk is of larger diameter than the interior of the valve holder 28.

5 In Fig. 5 of the drawings, I have shown a radiator 35 of ordinary construction, provided with a vent pipe 36, which, in turn communicates with a return pipe 37, and this return pipe discharges into the supply pipe 15 below the radiator valve. However, 10 this arrangement of the drain and return pipes forms no part of my present invention.

In practical use and assuming the parts of the valve to be in the position shown in Fig. 15 1 of the drawings, then it is obvious that a heating medium introduced through the supply pipe 15 will fill the interior of the valve casing and the valve holder 28. The heating medium will press equally in all directions 20 and therefore will exert a lifting pressure upon the valve holder 28 and a downward pressure upon the valve 31. It will also exert a downward pressure upon the pressure disk 33, and as the area of this disk is greater than that of the valve holder, it will hold the 25 edges of the valve holder firmly against the top of the partition 16 to thereby prevent leakage of the heating medium under the edges of the valve holder, and the downward pressure upon the top of the valve 31 will 30 prevent the leakage of the heating medium through the opening 18. By turning the valve stem a quarter revolution in either direction, the valve is made to stand between the openings 17 and 18, and thus a free passage-way for the heating medium is provided 35 between the inlet and outlet opening. A further advantage is gained by having the valve 31 slidingly connected with the guide 40 30 of the valve holder, because in this way the pressure of the heating medium within the valve chamber will be exerted in a downward direction upon the valve 31, tending to hold said valve firmly to its seat.

45 Having thus described my invention, what I claim and desire to secure by Letters Patent of the United States, therefor is—

1. A packless valve comprising a valve chamber provided with a partition having 50 an opening therein, a valve holder arranged within the casing and in contact with one side of the partition, a valve within the holder capable of covering and uncovering the opening in the partition, and a pressure plate connected with the valve holder and arranged within the casing on the opposite side of the partition.

2. In a packless valve, the combination of 55 a valve casing having an inlet opening and an outlet opening, and also having a partition provided with openings, through which communication may be had to the inlet opening from the outlet opening, a valve holder within the casing on one side of the 60 partition, so shaped as to permit passage

from one opening to the other through the partition, at all times, a valve within the holder capable of movement to position covering one of the openings in the partition, and a pressure plate connected with the valve 70 holder, and arranged within the casing on the opposite side of the partition.

3. In a packless valve, a valve casing provided with inlet and outlet openings, a partition within the valve casing having two 75 openings communicating respectively with the inlet and outlet openings, a valve holder within the casing in contact with one side of the partition, a valve within the holder in one position closing one of the openings in 80 the partition and a pressure plate connected with the valve holder and disposed within the casing on the opposite side of the partition and spaced apart from the partition with one side only exposed to the inlet opening.

4. In a packless valve, the combination of 85 a valve casing having inlet and outlet openings, a partition within the casing having two openings therein in communication respectively with the inlet and outlet openings, a valve holder within the casing in contact with one side of the partition and inclosing both of the openings therein, a valve within the holder in one position closing the 90 opening in the position that communicates with the outlet opening of the casing and a stem extending through the partition having the valve holder connected therewith, said stem projected through the partition to a 95 point spaced apart from the opposite side thereof and a pressure plate on said stem so disposed within the casing that only its side adjacent to the partition is exposed to the inlet opening.

5. In a packless valve, the combination of 100 a valve casing having an inlet opening and an outlet opening, a partition within the casing having two openings communicating respectively with the inlet and outlet openings, a hemispherical valve holder mounted within the casing on one side of the partition and inclosing both of the openings therein, a valve within the holder in one position closing the outlet opening, a stem connected 105 with the valve holder extended through the partition and a pressure plate on said stem having its surface nearest the partition exposed to the inlet opening of the casing.

6. In a packless valve, the combination of 110 a valve casing having an inlet opening and an outlet opening, a partition within the casing having two openings communicating respectively with the inlet and outlet openings, a hemispherical valve holder mounted with 115 in the casing on one side of the partition and inclosing both of the openings therein, a valve within the holder in one position closing the outlet opening, a stem connected with the valve holder extended through the 120 partition and a pressure plate on said stem having its surface nearest the partition exposed to the inlet opening of the casing.

125

130

partition and a pressure plate on said stem having its surface nearest the partition exposed to the inlet opening of the casing, said pressure plate having an exposed surface of greater area than that of the valve holder.

7. In a packless valve, the combination of a valve casing having an inlet opening and an outlet opening, a partition within the casing having two openings communicating respectively with the inlet and outlet openings, a hemispherical valve holder mounted within the casing on one side of the partition and inclosing both of the openings therein, a guide fixed to the holder, a valve slidingly

mounted on the guide and resting upon the partition capable in one position of covering the outlet opening in the partition, a stem connected with the valve holder extended through the partition and a pressure plate on said stem having its surface nearest the partition exposed to the inlet opening of the casing, said pressure plate having an exposed surface of greater area than that of the valve holder.

JOHN COLLIS.
